[57] CLAIM

The ornamental design for a rear sight for a pistol, as
shown and described.

DESCRIPTION

FIG. 1 is a view in rear perspective showing my design
for a rear sight for a pistol, the pistol slide shown in
phantom lines forming no part of my design;
FIG. 2 is a view in left side elevation thereof, the pistol
slide shown in phantom lines forming no part of my
design;

FIG. 3 is a view in right side elevation thereof;

FIG. 4 is a bottom plan view thereof;

FIG. 5 is a top plan view thereof;

FIG. 6 is a view in front elevation thereof;

FIG. 7 is a view in rear elevation thereof.

FIG. 2

FIG. 5

FIG. 3

FIG. 6

FIG. 4
